UNITED STATES PATENT OFFICE.

HUBERT H. EMISON, OF TIPTON, INDIANA, ASSIGNOR OF TWO-THIRDS TO
JOSEPH F. BERDG AND JAMES C. CARLISLE, OF FOSTORIA, OHIO.

DESIGN FOR A CASING FOR SPARK-ARRESTERS.

SPECIFICATION forming part of Design No. 28,493, dated April 19, 1898.

Application filed August 2, 1897. Serial No. 646,822. Term of patent 14 years.

To all whom it may concern:

Be it known that I, HUBERT H. EMISON, a citizen of the United States, residing at Tipton, in the county of Tipton and State of Indiana, have invented and produced a new and original Design for Casings for Spark-Arresters, of which the following is a specification, reference being had to the accompanying drawing, forming part thereof, wherein

- 10 I have represented my design in perspective.
It will be seen that the leading features of my design consist of two cylinders arranged one above the other in vertical alinement, the upper cylinder being designated as 1 and the lower cylinder being designated as 2; a convexed dome 3, surmounting the cylinder 1; an inverted elbow-pipe 4, extending laterally and

downwardly from the said upper cylinder near its lower end or base and alongside of the lower cylinder 2; a cylindrical rod 5, connecting the cylinders, and the saddle or flange 6 at the lower end of the lower cylinder 2.

Having described my invention, what I claim as new, and desire to secure by Letters Patent, is—

The design for a casing for spark-arresters herein shown and described.

In testimony whereof I affix my signature in presence of two witnesses.

HUBERT H. EMISON.
